UNITED STATES PATENT OFFICE.

WALTER B. ALLEN, OF ATTLEBORO, MASSACHUSETTS, ASSIGNOR TO ALLEN, SMITH AND THURSTON, OF ATTLEBORO, MASSACHUSETTS, A FIRM COMPOSED OF F. E. SMITH, H. A. THURSTON, JAMES MCNERNEY, AND W. B. ALLEN, OF ATTLEBORO, MASSACHUSETTS.

DESIGN FOR A COMB.

SPECIFICATION forming part of Design No. 35,463, dated December 24, 1901.

Application filed November 19, 1901. Serial No. 82,921. Term of patent 7 years.

To all whom it may concern:

Be it known that I, WALTER B. ALLEN, a citizen of the United States, residing at Attleboro, in the county of Bristol and State of Massachusetts, have invented and produced a new and original Design for Combs, of which the following is a specification.

As shown in the drawings, the leading or material feature of my design consists in the swelled portion of each tooth intermediate its extremities.

In detail my design is as follows: Depending from the comb-back a are the guard-teeth b b. The intermediate teeth are each shaped thus: The free extremity of each tooth c is pointed, but the width of the tooth gradually and symmetrically increases to form the medial portion of its body d. Thence the width of the tooth gradually diminishes until a point e near its inner extremity is reached. Thence the width of the tooth abruptly increases at its base f. Thus is formed a series of comb-teeth each possessing an intermediate swell and producing interstices intermediate each tooth of increased diameter toward the point and base of each tooth.

It is apparent that my design is applicable to all styles and qualities of combs.

Having thus described my invention, what I claim as new, and desire to secure by Letters Patent, is—

The design for a comb as herein shown and described.

In testimony whereof I have affixed my signature in presence of two witnesses.

WALTER B. ALLEN.
